UNITED STATES PATENT OFFICE.

LUDWIG DOEDERLEIN, OF CINCINNATI, OHIO, ASSIGNOR, BY DIRECT AND MESNE ASSIGNMENTS, TO TYPEWRITER IMPROVEMENT COMPANY, OF STAUNTON, VIRGINIA, A COPARTNERSHIP.

CARRIAGE-RETURN MECHANISM FOR TYPE-WRITERS.

SPECIFICATION forming part of Letters Patent No. 782,112, dated February 7, 1905.

Application filed July 11, 1903. Serial No. 165,169.

To all whom it may concern:

Be it known that I, LUDWIG DOEDERLEIN, a resident of 3064 Gilbert avenue, Cincinnati, Ohio, have invented a new and useful Improvement in Carriage-Return Mechanism for Type-Writers, which invention is fully set forth in the following specification.

This invention relates to type-writers, and more particularly to mechanism for automatically returning the carriage to its initial position.

In many forms of type-writers provided with the usual platen-carriage which reciprocates from right to left the carriage is turned by hand from its left-hand to its extreme right-hand position by first manipulating a lever to disengage the carriage from the rack-bar and then manually shifting the carriage to the desired right-hand position. By means of the present invention the type-writer is provided with a lever extending to the keyboard and carrying a suitable key which only has to be touched by the operator and the carriage will automatically return to its position from any point along the carriage-way. By another part of the invention means are provided whereby the carriage may be returned from left to right for only a portion of the way or to any desired extent—as, for example, when it is desired to return the carriage through but a few spaces in order to make corrections, &c.

Broadly stated, the invention consists in providing the type-writing machine having the usual carriage-advancing spring with a return-spring stronger than said advancing-spring, which return-spring is wound by a step-by-step movement through the medium of the key-levers during the operation of writing, the spring being retained in its wound position or under tension by means of a suitable retaining-pawl engaging the ratchet-wheel on the return-spring drum, which retaining-pawl is tripped by the carriage-return lever before mentioned. Additional means are provided for tripping the retaining-pawl, which means are connected by suitable devices with the rack-bar of the machine, so that when the rack-

bar is elevated by hand for shifting the carriage the act of elevating the rack-bar trips the retaining-pawl and leaves the carriage free to be reciprocated without any interference from said pawl. The carriage-return lever, which is depressed in order to trip the retaining-pawl when it is desired to return the carriage to its initial position, is provided with a suitable catch or other retaining device for holding the lever in position to retain the pawl out of engagement with the return-spring ratchet until the carriage has fully returned to its initial position, at which time or just before it reaches this position the carriage automatically trips the catch, so as to free the lever and retaining-pawl and permit the carriage-return lever to return to its normal position. As the extreme right-hand position of the carriage in most forms of type-writers is adjustable for the purpose of varying the left-hand margin, which adjustment is generally secured by what is known as an "adjustable" marginal stop, it is essential that the retaining-catch for the carriage-return lever should be tripped at the terminal movement of the carriage at whatever point the marginal stop may be adjusted. For this purpose the trip which actuates the catch to the carriage-return lever is itself adjustable, and preferably is mounted upon and adjustable simultaneously with the marginal stop.

The invention also consists in certain minor details of construction, which will be hereinafter more fully described and then pointed out in the claims.

The invention may receive various mechanical expressions, one of which is illustrated in the accompanying drawings, in which—

Figure 1 is a rear elevation with some of the parts broken away to render the illustration clearer. Fig. 2 is a left-hand elevation of Fig. 1. Fig. 3 is a diagrammatical perspective view of certain of the parts. Fig. 4 is a vertical section through the return-spring and its drum and certain connected parts, and Fig. 5 is a detail in perspective of the carriage-return-lever catch and the trip mechanism therefor.

Referring to the drawings, on any suitable framework 1 is mounted a bail-piece 2, pivoted in the rear part of the frame, which bail-piece is depressed by the action of the key-5 levers 3 in striking any given key.

4 is a lever pivoted at 5 to the framework of the machine, which lever has one of its arms connected to the bail-piece 2 by any suitable connecting device, (here shown as a yoke 10 6 and the swivel-link 7.) The opposite end of the lever 4 carries a pawl 8, engaging a ratchet-wheel 9 on the shaft 10, having bearings in the framework of the machine. The ratchet-wheel 9 and the pinion 11 are keyed to such shaft, 15 and the pinion engages a gear-wheel 12 upon spring-drum 14, to which drum is connected a pulley 15, over which extends a suitable cable 16, having one end secured to the periphery of the pulley and the other end secured at 17 20 to the carriage of the machine. In addition to the actuating-pawl 8 a retaining-pawl 18 is pivoted in such position as to engage the ratchet-teeth on the ratchet-wheel 9 and retain it while the pawl is in the act of moving 25 for reengagement with the ratchet-wheel. The lever 4 has a spring 19 normally operating to hold the end of the lever supporting the pawl 8 depressed.

The operation of the mechanism thus far 30 described will be readily understood. When the lever 3 is depressed from the keyboard, it operates to depress one end of the lever 4 and elevate the opposite end bearing the pawl, which thus turns the ratchet-wheel and 35 (through the intermediate clockwork-gearing) winds the spring in the spring-drum 14 and at the same time operates to unwind the cable 16 over the pulley a sufficient distance to permit the carriage to be advanced from the 40 right to the left by the ordinary carriage-advancing spring 20.

Pivoted upon the framework of the machine at 21^b is a lever 21, one of whose arms extends forward to the keyboard and carriage-key 22, 45 while the rear end of the said lever extends under the tails of the pawls 8 and 18, so that when the key 22 is depressed the rear end of the lever is elevated and operates to trip the two pawls 8 and 18 and free the spring in the 50 spring-barrel 14, whereupon it reacts to wind the cable 16 upon the pulley 15 and withdraw the carriage from left to right, this operation being secured by virtue of the fact that the spring in the spring-drum 14 is strong enough 55 to overcome and rewind the ordinary carriage-actuating spring 20. It is, however, frequently desirable in the operation of the machine to shift the carriage in either direction without returning it to its extreme right-hand 60 position, and in the act of doing this the operator elevates the rack-bar 27 of the machine, so as to enable the carriage to be shifted from left to right or right to left, as may be desired. In order that this movement may be 65 accomplished, means are provided in the pres-

ent invention whereby the pawls 8 and 18 shall be tripped and freed from engagement with the ratchet-wheel 9 whenever the rack-bar is thus elevated by the operator. For this purpose the bell-crank lever 24 is pivoted to the 70 frame at 25 and has one arm pivotally connected to a slide 26, which extends upward and is provided with a lip 26^a, Fig. 3, overhanging the top of the rack-bar. The other arm of the bell-crank lever 24 is connected by 75 a rod 28 to a crank-arm 29 on a shaft 30, which shaft also carries a wheel 31, having a projecting pin 32, lying normally under the tails of the pawls 8 and 18. Upon elevating the rack-bar 27 the connecting parts are operated 80 to cause the pin 32 to engage pawls 8 and 18 and free them from the ratchet-wheel 9.

The lever 21 is normally held in its elevated position by a spring 21^a, and to insure that the front end of the lever shall remain depressed and the pawls 8 and 18 disengaged from the ratchet-wheel 9 until the carriage has fully returned to its right-hand position a catch 23 is employed for engaging and retaining the rear end of the lever elevated until the terminal movement of the carriage to the right, when said catch may be automatically tripped through the medium of a trip-rod 23^a, Figs. 2 and 5.

Referring to Fig. 5, 33 is a marginal stop, 95 which may be of any desired construction, here shown as a member sliding upon a rail or bar 34, extending along the rear right-hand portion of the machine, said bar carrying a pawl which engages with a rack-bar 35 to hold 100 it in any of its adjusted positions. As the particular construction of this marginal stop is no part of the present invention, it need not be further described.

Pivoted upon the framework of the machine is a horizontally-extending plate 36, to which the rod 23^a is connected at 37, the point of connection being to one side of the medial longitudinal line of the plate 36. The other end of the rod 23^a is connected to 110 one arm of the bell-crank lever 23^b, the other arm of which carries the catch 23, the bell-crank lever being normally pressed by a spring 23^c, so as to push the catch 23 constantly against the face of the lever 21 when said lever is in 115 its normal position. When the keyboard end of the lever 21 is depressed and the rear end elevated, the spring 23^c acts to force the nose of the catch 23 under the lever 21 and hold it in its elevated position, in which position it 120 engages the tails of the pawls 8 and 18 and holds them disengaged from the ratchet-wheel 9. The act of the spring 23^c in forcing the nose of the catch 23 under the lever 21 depresses the arm of the bell-crank lever 23^b, to 125 which the rod 23^a is connected, thereby tilting the plate 36, as shown in Fig. 5.

Pivoted upon the marginal stop 33 is an L-shaped trip 39, one arm of which bears upon the opposite side of the axis of 130

the plate 36 from the point 37 where the rod 23^a is connected to said plate. The other arm of this L-shaped trip 39 projects upward and has a horizontal lip 40, which lies in the path 5 of the cam 41, supported upon and moving with the carriage. As the carriage returns from left to right the cam 41 passes under the lip 40 of the trip 39 and turns said trip upon its pivot, thereby depressing the horizontal arm of the trip, which is in engagement with the tilting plate 36. This action of the trip causes the pivoted plate 36 to rock on its axis and elevate the side of the plate to which the rod 23^a is connected, giving an upward pull upon said rod, and thus acting, through the bell-crank lever 23^b, to withdraw the catch 23 from under the carriage-return lever 21, which lever is thereupon at once returned to its normal position by its spring 21^a.

It is to be understood that the marginal stop 33 is adjustable along the entire length of the rack-bar 35, by which it is retained in its adjusted position, and that as the marginal stop 33 is shifted along its rack-bar it carries with it the trip 39, which is thus adjusted anywhere along the length of the rocking plate 36, so that the trip 39 will act to rock the plate at any point throughout its length and always just before the carriage is brought to rest by engagement with the marginal stop 33.

It will be observed that the mechanism for winding up the carriage-return spring is exceedingly simple in character, that the means for tripping said spring are controlled either from the keyboard or from the carriage rack-bar, and that the winding mechanism is automatically returned to its normally operative condition by the act of the carriage upon its 40 terminal return movement.

For the purpose of adjusting the tension of the carriage-return spring the spring-shaft 42 is provided with the ordinary form of escapement 43, or the spring may be wound by 45 an ordinary key engaging the square end 44 of the spring-shaft 42.

It is to be understood that the invention is not limited to the particular form of machine or carriage shown for illustrative purposes in 50 the drawings, as the invention is broadly applicable to any form of reciprocating carriage.

What is claimed is—

1. In a type-writer, the combination of a reciprocating carriage, means advancing said carriage during the operation of the machine, a carriage-return spring, winding mechanism for said spring operated by the key-levers, a device normally restraining said spring from action to return the carriage, a keyboard-lever for tripping said device and automatic means for holding said lever in engagement with said device during the return of the carriage.

2. In a type-writer, the combination of a re-

ciprocating carriage, and a carriage-advancing spring, with a carriage-return spring, a winding pawl and ratchet for said spring, operative connections between said pawl and ratchet and with the key-levers, a retaining-pawl, a trip-lever for said pawl having one end located at the keyboard and automatic means for holding said lever in engagement with said pawl during the return of the carriage.

3. In a type-writer, a reciprocating carriage, and its advancing-spring, a carriage-return spring operatively connected to said carriage, means normally restraining said return-spring from action, releasing means for controlling the advance of the carriage, and tripping mechanism for said restraining means operatively connected to said releasing means.

4. The combination of the carriage, the carriage-return spring, the rack-bar, the restraining-pawl for said spring, and pawl-tripping mechanism operatively connected to the rack-bar, whereby when the rack-bar is disengaged from its pinion the pawl is tripped and the return-spring acts upon the carriage.

5. The combination of the carriage, and carriage-return spring connected thereto, with the winding-pawl operated by the key-levers, the retaining-pawl, the rack forming part of the carriage-release mechanism, and tripping mechanism for tripping both pawls and operatively connected to the said rack.

6. In a type-writer, the combination of a carriage, a return-spring, a retaining-pawl, a keyboard trip-lever therefor, restraining and release mechanism whereby said trip-lever is held engaged to said pawl during the return movement of the carriage and is released at the end of such movement.

7. The combination of the carriage and its return-spring, with the retaining-pawl, the trip-lever therefor, the catch for holding said lever in tripping position, and automatic catch-releasing means.

8. The combination of the carriage and its return-spring, with the retaining-pawl, the trip-lever therefor, the catch for holding said lever in tripping position, and catch-releasing means actuated by the carriage.

9. The combination of the carriage and its return-spring, with the retaining-pawl, the keyboard trip-lever therefor, the catch for holding said lever in tripping position, and adjustable catch-releasing means.

10. The combination of the carriage and its return-spring, with the retaining-pawl, the trip-lever therefor, the catch for holding said lever in tripping position, the marginal stop for the carriage, and catch-releasing means mounted on said marginal stop.

11. The combination of the carriage and its return-spring, with the retaining-pawl, the trip-lever therefor, the catch for holding said lever in tripping position, a rocking member

connected to said catch, and means actuated by the carriage to rock said member, whereby the catch is tripped.

12. The combination of the carriage and its return - spring, with the retaining-pawl, the trip-lever therefor, the catch for holding said lever in tripping position, a rocking member connected to said catch, a tilting lever adjustable along said member, and means on the carriage engaging and tilting said lever, whereby the catch is tripped.

13. The combination with the carriage and its return-spring, with restraining means for said spring, devices for throwing and holding said restraining means out of action, and means actuated by the carriage for freeing said devices, whereby the spring is again placed under restraint.

14. In a type-writer, the combination of a reciprocating carriage, a carriage - return spring, winding mechanism for said spring operated by the key-levers, a device normally restraining said spring from action to return the carriage, a keyboard-lever for tripping said device, an automatic catch for holding said lever in engagement with said device during the return of the carriage, and catch-releasing means actuated by the carriage.

In testimony whereof I have signed this specification in the presence of two subscribing witnesses.

LUDWIG DOEDERLEIN.
